(57) **CLAIM**

The ornamental design for a cutting board device with cutout for bowl, as shown and described.

DESCRIPTION

FIG. 1 is a perspective view of a cutting board device with cutout for bowl showing my new design;

FIG. 2 is a side view (opposite side view is mirror image) thereof;

FIG. 3 is a front view thereof;

FIG. 4 is a back view thereof;

FIG. 5 is a top view thereof; and,

FIG. 6 is a bottom view thereof.

1 Claim, 4 Drawing Sheets

FIG. 1

FIG. 2

FIG. 3

FIG. 4

FIG. 5

FIG. 6
